UNITED STATES PATENT OFFICE

131,164

DESIGN FOR A TEXTILE FABRIC

Edwin Raphaels, New York, N. Y.

Application December 17, 1941, Serial No. 104,676

Term of patent 3½ years

To all whom it may concern:

Be it known that I, Edwin Raphaels, a citizen of the United States of America, residing in New York city, county of New York, and State of New York, have invented a new, original, and ornamental Design for a Textile Fabric, of which the following is a specification, reference being had to the accompanying drawing, forming part thereof.

Fig. 1 is a plan view of a piece of textile fabric showing my new design, a unit of which is contained between the dot and dash lines, the same being repeated in regular succession as indicated by the extension beyond the unit boundaries:

Fig. 2 is a cross sectional view taken on line 2—2 of Fig. 1.

My design comprises a series of raised rounded multi-color threads running in a vertical direction on a flat background.

I claim:

The ornamental design for a textile fabric, substantially as shown and described.

EDWIN RAPHAELS.
